UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,370**, dated August 26, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The ground of this carpet is, by oblique lines, divided into a series of partly-overlapping rectangular figures, A B C D. Each of these figures has checkered groundwork of different pattern from each of the others.

A vine, E, spreads its branches and tendrils over all the figures, and carries flowers *a a* within the fields B, C, and D, and buds *b b* within the field A, as shown.

I claim—

1. The design for a carpet, consisting of the figures A, B, C, and D, each having checkered background of different pattern, substantially as shown.

2. The design for a carpet, consisting of the figures A B C D, vine E, flowers *a*, and buds *b*, substantially as shown.

The above specification of my invention signed by me this 30th day of July, 1879.

HENRY HORAN.
